DESIGN FOR A REFRIGERATED DISPLAY CASE

John R. Caulk, Jr., Ladue, and Russell E. Davis,
St. Louis, Mo., assignors to Hussmann-Ligonier
Company, St. Louis, Mo., a corporation of
Missouri

Application November 28, 1941, Serial No. 104,364

Term of patent 14 years

To all whom it may concern:

Be it known that we, John R. Caulk, Jr., and Russell E. Davis, citizens of the United States and residents of Ladue, in the county of St. Louis and State of Missouri, and of the city of St. Louis, and State of Missouri, respectively, have invented a new, original, and ornamental Design for a Refrigerated Display Case, of which the following is a specification, reference being had to the accompanying drawing, forming part thereof.

Fig. 1 is a top plan view of a refrigerated display case, showing our design;

Fig. 2 is a front elevational view, with a portion of the glass front wall broken away to disclose the lower portion of the rearwardly slanting mirror mounted in the top of the case;

Fig. 3 is an end elevational view; and

Fig. 4 is an end elevational view with parts broken away to show said rearwardly slanting mirror and the glass end wall.

We claim:

The ornamental design for a refrigerated display case, as shown and described.

JOHN R. CAULK, JR.
RUSSELL E. DAVIS.
